(57) **CLAIM**

The ornamental design for a suspender from brassiere, as shown and described.

DESCRIPTION

FIG. 1 is a front elevation view of a suspender from brassiere, showing my new design;

FIG. 2 is a rear elevation view thereof;

FIG. 3 is a right side elevation view thereof;

FIG. 4 is a left side elevation view thereof;

FIG. 5 is a top plan view of FIG. 1;

FIG. 6 is a bottom plan view of FIG. 1;

FIG. 7 is a front view, shown in an alternate configuration; and,

FIG. 8 is a front view thereof, shown with the clips exposed. The broken lines represent the portions of the design that form no part of the claim.
